UNITED STATES PATENT OFFICE.

JOSEPH J. GANNON, OF PORT HURON, MICHIGAN, ASSIGNOR TO DIAMOND CRYSTAL SALT COMPANY, OF ST. CLAIR, MICHIGAN, A CORPORATION OF MICHIGAN.

COMBINED DISCHARGE AND CLOSURE DEVICE.

Application filed May 26, 1924. Serial No. 715,990.

To all whom it may concern:

Be it known that I, JOSEPH J. GANNON, a citizen of the United States, residing at Port Huron, in the county of St. Clair and State of Michigan, have invented certain new and useful Improvements in Combined Discharge and Closure Devices, of which the following is a specification, reference being had therein to the accompanying drawings.

10 This invention relates to a combination discharge and closure device for containers adapted for holding granular matter or any material that may flow by gravity, the device being particularly designed for a container holding salt, sugar and other granular edibles or condiments.

My invention aims to furnish a container with a closure member that normally closes a discharge opening of the container, the closure member being arranged so that the end thereof is pivotally held in engagement with the container so that the opposite end of the closure member may be swung to an open position to permit of granular material flowing from the bottom of the container. The closure member is made from a blank pressed to provide a trough-like discharge chute with the side walls limiting the opening movement of the closure member and cooperating with the bottom wall of the closure member in affording pivotal means for one end of the closure member, while the opposite end of the closure member has a lip to limit the closing movement of the closure member and at the same time permit of the closure member being sealed.

The construction entering into my invention will be hereinafter described and then claimed, and reference will now be had to the drawing, wherein—

Figure 1 is a perspective view of a portion of the container provided with a closure member showing the same in an open position;

Fig. 2 is a bottom plan of the closure member;

Fig. 3 is a bottom plan of a portion of the container showing the opening for the closure member;

Fig. 4 is an enlarged longitudinal sectional view of the closure member in a closed position;

Fig. 5 is a similar view of the closure member in an open position;

Fig. 6 is a cross sectional view taken on the line VI—VI of Fig. 5;

Fig. 7 is a perspective view of a detached closure member, and

Fig. 8 is a plan of a blank from which the closure member is made.

In the drawing, the reference numeral 1 denotes a container and a wall 2 of said container is provided with a trapezoidal opening 3, that is, an opening having side walls tapering inwardly from what I consider the inner end of the opening to the outer end thereof, in order that said opening may accommodate a tapering discharge and closure device.

The combined discharge and closure device is made from a blank or single piece of material which is bent on the dotted lines 4 to provide a connecting or bottom wall 5 and side walls 6, with said walls disposed at a right angle to the bottom wall 5 so as to form a troughlike chute which tapers inwardly from the inner end of the closure device to the outer end thereof.

The side walls 6 have the inner ends thereof cut away as at 7, to form lugs 8 and said lugs are bent in slightly so as to underlie the wide inner edge 9 of the bottom wall 5 and co-operate therewith in gripping the inner wall 10 of the opening 3. The arrangement of the lugs 8 and the wall 5 are such that the inner end of the closure device may pivotally support said device so that the outer end of the device may be swung in an arc, which is defined by a lip 11 at the outer end of the bottom wall 5, and outturned or return bent flanges 12 of the side wall 6. These side walls have the outer ends thereof provided with arcuated edges 13 which are adapted to cooperate with the inner end of the closure device in frictionally holding the device in an adjusted position in the opening 3, it being noted in Figs. 4 and 5 that the arcuated edges 13 bind against the wall 11^a at the outer end of the opening 3, while the inner ends of the walls 6 bind against the inner wall 10 of the opening 3.

It is therefore possible to shift the discharge and closure device, by means of the lip 11, to a desired inclination relative to the wall 2 and thus provide a discharge opening or chute for the flow of a desired quantity of granular matter within the container 1.

When opening the discharge and closure

device the flanges 12 of the side wall 6 impinge against the inner face of the wall 2, at tapering sides of the opening 3, and thus define an extreme open position of the closure device, while the lip 11 engages the outer face of the wall 2 to define a closed position of the device.

With the closure device in a closed position the side walls 5 may extend into the matter in the container 1 and the bottom wall 5 will cooperate with the wall 2 in forming a bottom or end wall of the container. Any form of seal or label can be placed over the closure device or a portion thereof to retain it in a closed position until it is desired to use the contents of the container, when the seal may be broken, the closure device opened, and the container 1 inverted to permit of the matter in the container flowing by gravity therefrom. By placing the container in an upright position the closure member can be closed and need not be sealed again. With the closure member in an open position the inner wide end thereof permits of granular matter to flow towards the small restricted end of the closure member, and as before stated, said closure member can be shifted to regulate the amount of discharge from the container.

I attach considerable importance to the one-piece construction of the discharge and

closure device, and particularly the construction of the side walls which afford a pivot for the closure device and limit the opening movement thereof. It is obvious that such a device can be advantageously used in connection with cardboard cartons and containers, and while in the drawing there is illustrated a preferred embodiment of my invention, it is to be understood that the structural elements are susceptible of such variations and modifications as fall within the scope of the appended claim.

What I claim is:

A combined discharge and closure device for a container having a wall opening, comprising a trough-like member pressed from a blank to form a trough tapering inwardly from its receiving end to its discharge end and providing side walls and a connecting wall, said trough-like member being mounted in the wall opening, said member having its side walls terminating in lugs extending under the connecting wall of said member and co-operating therewith in pivotally supporting the receiving end of said member and means for limiting the opening movement of the discharge end of said member.

In testimony whereof I affix my signature.

JOSEPH J. GANNON.
